DEVICE FOR ATTACHING AN ENCLOSURE
ABOUT A HIGH TEMPERATURE CASING
Roger D. Sidener, Westfield, N.J., assignor to Foster
Wheeler Corporation, New York, N.Y., a corporation
of New York
Filed Apr. 23, 1962, Ser. No. 189,400
1 Claim. (Cl. 189—34)

This invention relates to casings operable at high temperatures, such as furnace or boiler walls. It is a device for attaching an outer enclosure to the casing.

Because of different operating temperatures between the casing and the enclosure, the attaching device must be capable of accommodating relative movement therebetween. The present advance contemplates a movable connection for this service. An angle and a clip are provided. The angle has a flange movable with the casing relative to the clip without disengagement therefrom.

The accompanying drawing is an isometric section showing a portion of a furnace wall embodying this invention.

In the drawing, longitudinal casing 1 is subjected to a high temperature while enclosure 2 is substantially at ambient temperature.

Enclosure 2 is supported from casing 1. Toward this objective angle 3 is connected to casing 1 by fillet welds 4. Longitudinal flange 6 engages in recess 7 (with clearance 8) defined by clip 9 which in turn is connected to enclosure 2. Sliding of flange 6 in recess 7 accompanies longitudinal movement between casing 1 and enclosure 2. Transverse movement of casing 1 relative enclosure 2 is accompanied by sliding relative clip 9.

Enclosure 2 is fabricated of first panel 13 and second panel 14. Terminal lip 16 on first panel 13 projects outward relative enclosure 2. Second panel 14 defines end 17 folded over terminal lip 16 to form a joint. Clip 9 is disposed in sandwiched engagement between terminal lip 16 and end 17 for connection to enclosure 2.

It will be apparent that wide changes can be made in the shown embodiment without departing from the spirit of invention defined by the claim.

What is claimed is:

An apparatus for attaching an enclosure to a vertical

2

planar portion of a casing with the casing operable at a higher temperature than the enclosure,
the apparatus comprising

an elongated metallic angle connected to the casing and having an upward projecting longitudinally extending flange spaced from the casing,

an elongated metallic clip connected to the enclosure and defining a longitudinally extending downward opening recess adapted to receive at least a portion of the upward projecting flange in sliding engagement therein,

the flange being movable with the casing relative to the clip,

the flange having an outer surface on the side thereof removed from the casing,

insulation lining the outer surface between adjacent surfaces of the flange and clip to minimize heat transfer from the casing to the enclosure, the insulation and flange making a close fit in said recess,

the enclosure comprising a first and a second panel arranged in contiguous relationship and aligned in a vertical plane,

the first panel defining a terminal lip projecting outward relative the enclosure,

the second panel defining an end folded over the terminal lip to form a joint,

the clip disposed in sandwiched engagement between the terminal lip and the end for connection to the enclosure.
